UNITED STATES PATENT OFFICE.

REGINALD G. STANDERWICK, OF LYNN, MASSACHUSETTS, ASSIGNOR TO GENERAL ELECTRIC COMPANY, A CORPORATION OF NEW YORK.

VAPOR ELECTRIC DEVICE.

1,128,070.

Specification of Letters Patent.

Patented Feb. 9, 1915.

Application filed October 4, 1913. Serial No. 793,480.

To all whom it may concern:

Be it known that I, REGINALD G. STANDERWICK, a subject of the King of Great Britain, residing at Lynn, in the county of Essex and State of Massachusetts, have invented certain new and useful Improvements in Vapor Electric Devices, of which the following is a specification.

The present invention relates to the operation of vapor electric devices, and particularly to the operation of mercury vapor devices of the high pressure type, such as the "quartz lamp".

It is the main object of my invention to safe-guard the operation of vapor devices against excessive energy consumption and consequent overheating, particularly on series circuits.

The high pressure type of mercury vapor device differs from the low pressure type not only in the higher temperature and high efficiency attainable by the use of a refractory envelop, but also in its electrical operating characteristics. For example, at a certain critical current value, the voltage consumption in the high pressure lamp increases steadily with but very little, or practically no increase in current. In other words, if such a device were operated on an ordinary variable voltage, constant current circuit in the neighborhood of this critical current value, the voltage drop across the lamp would rise continuously until the wattage had increased to a point sufficient to destroy the lamp by excessive heating.

In accordance with my invention, a vapor electric device having this peculiar volt-ampere characteristic is provided with an automatically controlled energy-consuming means, for example, a resistance, to divert current from the vapor device when the voltage consumed by the vapor device exceeds a predetermined limit by reason of an increase of current.

In the accompanying drawings, Figures 1 and 2 are diagrams illustrating a system in which energy is diverted from the vapor electric device by a magnetically-controlled resistance; and Fig. 3 shows an arrangement in which a self-reducing resistance is connected permanently across the lamp.

As shown in Fig. 1 a mercury vapor electric lamp tube 1, having a cathode consisting of mercury, or other easily vaporizable material, contained in a chamber 2, and an

anode 3 of tungsten, or other highly refractory conductive material, is connected to conductors 4 and 5 which, for purpose of illustration, may be assumed to be fed by a variable voltage source. A high pressure lamp is commonly operated in a fused quartz envelop and is operated at high vapor pressure as described, for example, in Küch Patent #883,725 of 1908, and an application, Serial No. 753,946, filed March 13, 1913 by Dr. E. Weintraub. The lamp is supported by straps 6 and 7, the former being rotatably mounted upon a fixed support 8 and the latter connected through a link 9 to the core 10, of an electromagnet 11. This magnet is connected in series with resistance 12, and contacts 13 and 14 to the lines 4 and 5. The contact 13 is connected to the armature of a series magnet 15 and the contact 14 is controlled by magnet 16 connected across lines 4 and 5 by conductor 17, in shunt with the lamp. The lamp is started when a current of suitable voltage is applied by a rise of core 10 which tilts the lamp and causes a flow of mercury along its length to make contact with the anode, thus completing a circuit through the lamp. The completion of an electric circuit in the lamp energizes the series magnet 15, which lifts its core thereby breaking the circuit of the magnet 11 and allowing the lamp to descend to its original position. An arc is thereby struck in the well known manner by the mercury receding to the cathode chamber.

As the lamp may be operated at highest efficiency near the critical value of current, it is desirable that the current maintained should be quite close to the current value at which the voltage begins to rise abruptly without further increase of current. If any change in external conditions or of the electrical characteristic of the circuit should take place, the lamp would be endangered by overheating. Should such a condition occur and the voltage consumption increase unduly, the magnet 16 will lift its armature, completing a circuit through the coil 11 and resistance 12 in parallel with the lamp. The resistance of this circuit should be so proportioned that it will shunt but a small part of the energy from the lamp, enough to reduce its temperature and vapor pressure and restore it to normal operating condition. In the case of a 320 watt, four ampere quartz mercury lamp, the resistance of 110

the shunt circuit should be about 110 ohms. As soon as the voltage across the device has fallen below the predetermined limit at which magnet 16 becomes energized, the contact 14 will fall away from contact 13, thereby opening the circuit through the shunt path and allowing the lamp to assume its normal operation. This action will be almost momentary, or in other words, the coil 16 will cause the resistance 12 and the starting magnet to "float" across the tube intermittently in accordance with any abnormal rises of voltage.

In the system shown in Fig. 2a starting magnet 11, a series magnet 15 and a regulating shunt magnet 16 are provided as before but there are provided in addition two movable contacts 13 and 14, a fixed contact 18 and a resistance 19 which is connected to the line 4 through a conductor 17, and at its other end to the movable contact 14. The fixed contact 18 is connected to the line 5 of the supply circuit. In this system the lamp is started as heretofore explained by the magnet 11 drawing up its core 10 when energy is supplied.

When the arc in the device 1 is started the circuit through magnet 11 is interrupted by the series magnet 15 separating the contact 13 from the contact 18, to the former of which the lifting magnet 11 is connected through the conductor 20, thereby breaking its circuit by the separation of contact 13 from the fixed contact 18. In this case the resistance of the lifting magnet circuit need be proportioned only to insure the series magnet 15 taking enough current to open the lifting magnet circuit when the mercury stream bridges the cathode and anode in the lamp at starting. The resistance of the starting magnet circuit is not used exclusively to reduce the current in the lamp but a separate resistance 19 is used. The resistance 19 is proportioned to divert only a small part of the current from the vapor device when connected in shunt therewith. For example, in the case of a 320 watt mercury vapor quartz lamp operating normally with a voltage consumption of about 80 volts, the resistance 19 should be about 200 ohms. In case the voltage across the terminals of the device rises above a predetermined value, the magnet 16 will raise its core to bring contact 14 against contact 18, thereby shunting the device with the resistance 19. This will divert energy from the device thereby reducing its temperature and vapor pressure and restoring it to normal operation. When the voltage across the device has again dropped below the critical value the contacts 14 and 18 separate and open the circuit through the resistance 19.

In case the device should become damaged in any way and its voltage rises after the resistance 19 has been shunted across it, the

current diverted by the resistance 19 will increase and as the current is diverted not only from the vapor electric device but also from the series magnet 15, this magnet will finally become so weakened that it will permit its core to descend and allow the contact 13 to touch the contact 18, thereby also introducing the starting magnet 11 in shunt with the lamp. This additional shunt circuit will divert sufficient current from the lamp to put out the arc.

In the arrangement shown in Fig. 3, a self-reducing resistance 21 is permanently connected in shunt with the vapor device 1. The regulator 21 should have a sharp breakdown characteristic, such as is possessed by boron or boro-carbon. A self-reducing cut-out of this nature is described in Patent #1,019,390 issued March 5, 1912, to Ezechiel Weintraub. The regulator is proportioned to shunt only a negligible amount of current from the lamp when it is operating at normal voltage but when the voltage rises unduly the resistance of the regulator will suddenly be decreased, thereby diverting current from the lamp so as to reduce its vapor pressure and temperature as already described in connection with Figs. 1 and 2. As the voltage across the device is restored to normal the high resistance of the regulator 21 will be automatically restored, thus forcing all but a negligible part of the current to pass through the vapor device.

What I claim as new and desire to secure by Letters Patent of the United States, 100 is:—

1. The combination of a vapor electric device the operating voltage of which at a critical value increases greatly with a slight increase of current, and means responsive to a rise of voltage consumed by said device above a predetermined limit for diverting a fractional part of the energy from said device.

2. The combination of a high pressure vapor electric device, a resistance proportioned to carry a fractional part of the energy consumed by said device at a given voltage and means responsive to an excessive increase of voltage consumed by said device for connecting said resistance in shunt with said device.

3. The combination of a high pressure mercury vapor quartz lamp, a resistance proportioned to carry a fractional part of the energy consumed by said lamp at a given voltage and means responsive to a rise of voltage drop in the lamp above a predetermined limit to connect said resistance in shunt with said lamp while the voltage consumption in the lamp is in excess of the value at which the voltage increases without substantial increase of current.

4. The combination of a high pressure mercury vapor lamp, means for supplying 130

substantially constant current at variable voltage to said lamp, a resistance proportioned to carry a fractional part of the energy consumed by said lamp at a given voltage and an electromagnet connected in shunt with said lamp proportioned to operate when the voltage across the terminals of the lamp increases above a critical value at which further increase of voltage is accompanied with little or no increase of current, and connections for shunting said lamp through said resistance when said magnet operates.

5. The combination of a high pressure vapor electric device, a resistance proportioned to consume a fractional part of the energy consumed by said device at a given voltage, means responsive to a rise of voltage on the terminals of said device above a predetermined value to connect said resistance in shunt with said lamp, a second resistance proportioned to carry sufficient energy to extinguish said device when connected in conjunction with the first resistance in shunt with said device, and means for connecting said second resistance in shunt with said device when the operating current falls below a predetermined value.

6. The combination of a source of electric energy of substantially constant current, 30 a high pressure vapor electric device connected thereto, and means responsive to a rise of voltage consumption of said device above the critical value at which an increase of voltage is accompanied by no substantial 35 increase of current for decreasing the energy supply of said device while the voltage consumption exceeds this critical value.

7. The method of operating a high pressure vapor arc with a constant current variable voltage supply, which consists in normally maintaining the impressed voltage close to the critical value at which a further increase of voltage is accompanied by no substantial increase of current and when 45 the voltage consumption tends to exceed this value substantially reducing the energy supply until the voltage consumption is decreased below the critical value.

In witness whereof, I have hereunto set 50 my hand this 22 day of September, 1913.

REGINALD G. STANDERWICK.
